UNITED STATES PATENT OFFICE.

GEORGE O. DRAPER, OF HOPEDALE, MASSACHUSETTS, ASSIGNOR TO
GEORGE DRAPER & SONS, OF SAME PLACE.

SUPPORT FOR SPINNING-SPINDLES.

SPECIFICATION forming part of Letters Patent No. 410,355, dated September 3, 1889.

Application filed June 15, 1889. Serial No. 314,485. (No model.)

To all whom it may concern:

Be it known that I, GEORGE O. DRAPER, of Hopedale, county of Worcester, State of Massachusetts, have invented an Improvement in 5 Supports for Spinning-Spindles, of which the following description, in connection with the accompanying drawing, is a specification, like letters on the drawing representing like parts.

10 This invention has for its object to improve that class of spindle wherein the oil used to lubricate the spindle is kept in circulation up over the top of the bearing, and is thrown inside the whirl, and by it returned back into 15 the supporting-case.

In accordance with my invention, the lower end of the sleeve-whirl is of such diameter that the annulus or ring surrounding it may be lifted above the lower edge of the groove 20 and up to the band in the band-groove, when it is desired to introduce the snout of an oil-can into the space within the curb of the supporting-case to oil the spindle and bearing. This annulus or ring is shown as without 25 holes, so that it actually excludes the entrance of lint and dirt into the bearing, and oil is prevented from escaping to the outside of the supporting case or rail.

The drawing shows in partial elevation and 30 section a spindle and bearings therefor, together with the annulus or ring, the latter being shown by dotted lines as elevated for oiling.

The rail A sustains a supporting-case B, 35 which is held in place by a nut C, of usual construction.

The spindle D has an attached sleeve-whirl D', the lower end 2 of which below the band-groove 3 is of substantially the diameter of 40 the whirl at the point 4, designating the lower edge of the groove of the whirl which receives the band, the said lower end 2 of the said sleeve-whirl constituting by its external portion a guide for the annulus or ring a, so that 45 the latter, were it not for the band in the band-groove, would cross the band-groove.

The annulus or ring a will preferably have a flange a' to aid in lifting it when it is desired to enter the snout of an oil-can into the 50 space below the lower end of the said sleeve-

whirl and between it and the curb 5 of the supporting-case, to enable the bearing to be oiled. The annulus or ring is preferably without any transverse oil-hole, and in practice it enters a groove cut in the curb 5, and 55 has a loose fit about the sleeve-whirl, the space between them being, however, sufficient to permit of the proper movements of the spindle in centering itself.

The lower end of the sleeve-whirl is of such 60 shape and length as to enable the annulus or ring to be lifted above the lower edge 4 of the band in the band-groove, which could not be done in any spindle construction known to me.

The nearer the annulus or ring can be moved 65 to the line of band-pull, (the center of the whirl, where it is of least diameter,) the shorter may be the sleeve-whirl, and yet enable it to co-operate with the annulus or ring, while the latter bridges the space between the lower end 70 of the whirl and the curb of the supporting-case.

Between the bolster b in the supporting-case and the spindle I have shown a series of inclined grooves e, so made as to enable the 75 oil to be lifted by the spindle in its rotation, the oil rising above the top of the bolster and bolster-case, and being discharged against the inner side of the whirl, down which it runs, it being discharged from the lower end of the 80 sleeve-whirl at a point below the top of the annulus or ring a, the interior of the latter directing the oil into the interior of the curb, and preventing any oil from getting outside the said curb and on the rail. The oil entering 85 the supporting-case inside the curb 5 passes to the bolster through the oil-hole 8, and then through holes 10 to the spindle.

To insure the discharge of the oil from the bolster directly to the interior of the whirl 90 the upper end of the bolster will be extended above the supporting-case.

I do not desire to limit my invention to the particular means used to cause the upward circulation of oil in the bolster, as instead of 95 the grooves I may use any other well-known and usual means—as, for instance, the taper of the spindle may be such as to cause the oil to rise between it and the bolster.

By the construction herein described the oil 100

is kept in constant circulation so long as the spindle runs.

It is obvious that the operation of the annulus *a* would be the same with relation to 5 the sleeve-whirl whether the bolster-bearing in the supporting-case is separate therefrom or integral therewith.

The bolster-bearing, if separate from the supporting-case, will preferably be loose 10 therein.

I am aware that the lower end of the sleeve-whirl has been surrounded by an annulus having a slight vertical movement when oiling; but prior to my invention I am not 15 aware that the said guide has been large enough to permit the ring to rise up to and partially across the band-groove, if desired.

I claim—

The combination, with a supporting-case 20 having a curb, a bolster-bearing, and an oil-

hole, and a sleeve-whirl spindle having an extension 2 below the band-groove, the diameter of the said extension being as great as that of the sleeve-whirl at the lower end of the band-groove, of an annulus or ring *a*, 25 adapted to be lifted vertically outside the said extension up to and across the band-groove, thereby uncovering the space between the lower end of the whirl and the cover of the supporting-case, the lower end of the said annulus or ring entering the said curb, to operate substantially as described.

In testimony whereof I have signed my name to this specification in the presence of two subscribing witnesses.

GEORGE O. DRAPER.
